COMBINED SINK TRAY AND DISH DRAINER

Retha Bachand, 4195 Fisher Road NE.,
Salem, Oreg. 79303

Filed Sept. 3, 1968, Ser. No. 13,377

Term of patent 14 years

Int. Cl. D7—06

U.S. Cl. D44—29

FIG. 1

FIG. 2

FIG. 3

FIG. 4

FIGURE 1 is a top plan view of a combined sink tray and dish drainer showing my new design.

FIGURE 2 is an elevational view from the bottom of FIG. 1;

FIGURE 3 is an elevational view from the right of FIG. 2;

FIGURE 4 is a reduced scale perspective view of the article in association with a sink shown in broken lines for illustrative purposes only; and

FIGURE 5 is a sectional view on line 5—5 of FIG. 1.

I claim:

The ornamental design for a combined sink tray and dish drainer, as shown and described.
